UNITED STATES PATENT OFFICE.

ELBRIDGE J. STEELE, OF NEW HAVEN, CONNECTICUT, ASSIGNOR TO
SARGENT & CO., OF SAME PLACE.

IMPROVEMENT IN SNAP-HOOKS.

Specification forming part of Letters Patent No. 172,355, dated January 18, 1876; application filed November 23, 1875.

To all whom it may concern:

Be it known that I, ELBRIDGE J. STEELE, of New Haven, in the county of New Haven and State of Connecticut, have invented a new Improvement in Snap-Hooks; and I do hereby declare the following, when taken in connection with the accompanying drawings and the letters of reference marked thereon, to be a full, clear, and exact description of the same, and which said drawings constitute part of this specification, and represent, in—

Figure 1, top view; Fig. 2, side view; Fig. 3, longitudinal central section; Fig. 4, modification.

This invention relates to an improvement in the article known to the trade as "snap-hooks;" and it consists in the combination and arrangement as fully hereinafter described.

A is the hook proper, formed on a shank, B, terminating in a loop, C, or other device for attaching the hook. The hook A is open relatively to the shank in substantially the usual manner. D is the tongue pivoted in a recess in the shank, as at a, with a spring, b, arranged in connection with the said tongue, the tendency of which is to throw the tongue downward so as to open the hook, as indicated in broken lines, Fig. 3. In the rear of the tongue, and in the recess of the shank, a lever, E, is arranged upon a fulcrum or pivot, f. The forward end of the lever is formed to fit the upper surface of the rear end of the tongue above the pivot, whatever that may be. Below the line of the two pivots the end of the lever is made substantially concentric with the pivot of the lever and the rear of the tongue of corresponding form; hence the pressure upon the tongue to depress it, as for opening the hook, is resisted by the end of the lever, so that when the tongue is closed the lever practically locks it in that closed position. The lever extends to the rear so as to form a convenient thumb-piece, F, by which the rear end may be depressed, and consequently the for-

ward end raised, as indicated in broken lines. So soon as the bearing-surface of the forward end of the lever is raised above the pivot of the tongue, then the reaction of the spring beneath the tongue will open it, as also indicated in broken lines. When the lever is free the spring forces the forward end downward to bear upon the tongue and turn that up into its closed position, the spring of the lever being more powerful than that of the tongue.

The same combination of lever and tongue may be made, as shown in Fig. 4, without the locking-power of the lever by simply extending the tail-piece of the tongue, as seen in Fig. 4, to the rear beneath the lever, so that pressure upon the tongue to open it will raise the forward end of the lever; but I prefer the locking construction.

By this construction an easy method is afforded for opening the hook for attachment or detachment.

I am aware that it is not new to combine a lever with the tongue of a snap-hook, so that depressing the lever may open the hook, as such may be found in the patent of J. B. Sargent, November 12, 1867; therefore I do not wish to be understood as broadly claiming such a construction.

I claim—

1. The combination, in a snap-hook, of the hook A, tongue D, and lever E, the meeting or bearing surfaces between the said lever and tongue being substantially concentric with the pivot of the tongue, as and for the purpose described.

2. In combination with the hook A, the tongue D, and lever E, each provided with independent springs, substantially as described.

ELBRIDGE J. STEELE.
